AXMINSTER SETTING FRAME

Conrad C. Blom, Springfield, Mass., assignor to
Bigelow-Sanford Carpet Co. Inc., Thompson-
ville, Conn., a corporation of Massachusetts

Application October 21, 1935, Serial No. 45,838

31 Claims. (Cl. 28—55.5)

This invention relates to setting or winding frames employed for winding yarn on spools to be used in the weaving of Axminster rugs, and it particularly pertains to improvements in the construction of machines of that character whereby to obtain a more uniform and more accurately measured winding of the yarn on the spools than has been obtainable heretofore.

In the winding of spools on such frames it is essential that substantially the same predetermined amount of yarn be wound on all of the spools, both overwound and underwound, and I have found that that result can be accomplished by providing a tension on the yarn adjacent the spool as it is being wound which is not only of approximately the same predetermined amount for all spools being wound, both overwound and underwound, but which is also substantially unvarying as the spools fill with yarn. The preferred form of apparatus and method embodying my invention insures the proper substantially unvarying tension around the spool by positioning the three winding rolls at substantially equal distances around the periphery of the spool, which rolls are yieldingly pressed thereagainst and are rotated at a predetermined differential in speed to exert a drag on the yarn at the points of contact therewith. The predetermined amount of tension which is thereby produced is preserved as the spool fills by maintaining the substantially equidistant relationship of the spools while permitting a gradual yielding divergence of the rolls as required to accommodate the growth of yarn on the spool.

The foregoing characteristics of my apparatus are preserved for both overwinding and underwinding and in that manner I insure an equal amount of tension and hence a uniformity in the amount of yarn wound in either direction.

Accuracy of measurement of the yarn wound on the spool is not dependent solely upon the accuracy of the winding operation of the setting frame, but also depends upon the manual operations of drawing off the yarn at the completion of the winding of one spool, clamping up the ends of the yarn strands on the wound spool, and overlapping the severed ends of yarn around the next succeeding spool to be wound. Heretofore, inaccuracies have arisen through the failure of the operative to draw off the same amount of yarn during these operations and my invention seeks to improve on prior machines and methods of this character by the provision of means and methods which limit to a predeter-

mined amount, the yarn available to the operative for these operations.

These and further objects and advantages of my invention will appear from a more detailed description thereof taken in connection with the accompanying drawings, in which,

Fig. 1 is a diagrammatic view showing the yarn passing from the creel to the spool in winding position contiguous to the winding rolls;

Figs. 2-4 inclusive are diagrammatic views of the winding rolls indicating the manner in which they are positioned for winding and the manner in which they diverge from each other as the spool fills;

Figs. 5 and 6 diagrammatically illustrate one way in which the rolls may be driven in accordance with my invention for overwinding and underwinding respectively;

Fig. 7 is a side elevation view of my setting frame;

Fig. 25 is a vertical section on the line 25—25 of Fig. 23.

10 By way of introduction to the description of the preferred embodiment of my invention, reference is made to Figs. 1-6 inclusive wherein I have diagrammatically illustrated the disposition and mode of operation of the winding rolls of one embodiment of my invention.

15 As indicated diagrammatically in Fig. 1, the yarn 1 is fed, as is customary, from the bobbins 2 comprising the creel 3, through a combing reed 4 to a pair of idler rolls 5 and 6 which are associated with a counting mechanism for measuring the yarn and which also produce a certain tension on the yarn as it passes through a second reed 10, over an idler roll 11 and thence to the spool 12 on which it is being wound. Movement of the 20 yarn from the creel 3 through the aforesaid mechanism and to the spool 12 is effected by three winding rolls 20, 21 and 22 which are disposed in peripheral engagement with the spool 12 and the yarn wound thereon.

25 30 As indicated in Fig. 2, wherein is shown the position of the winding rolls 20, 21 and 22 at the beginning of the winding operation, the rolls are then disposed at equal intervals around the periphery of the spool 12. As the spool 12 fills with 35 yarn, I preserve the equidistant relationship of the rolls while permitting divergence of the rolls to accommodate the growth of yarn, until the end of the winding operation when the rolls are positioned as illustrated at 20B, 21B and 22B of Fig. 3. To preserve this equidistant relationship 40 at all stages of the winding, I may mount the winding rolls each in sliding bearings extending radially from the axis of the spool 12, but I have found that for simplicity of construction, one of the rolls, such for example as roll 21, may be 45 mounted in stationary bearings and the rolls 20 and 22 may be mounted in bearings carried by crank arms which are pivoted to the frame of the machine and are adapted to swing in arcs about 50 their pivots to accommodate the growth of yarn on the spool. This construction I have diagrammatically illustrated in Fig. 4 wherein the roll 20 is indicated as mounted in a bearing which swings about the point 20' as a pivot and the roll 22 is 55 mounted in a bearing which swings about the pivot 22'. The disposition of the pivots 20' and 22' and the length of the radii to the axes of the rolls 20 and 22 can readily be chosen to provide 60 the equidistant relationship of the rolls 20 and 22 relative to each other and to the stationary roll 21 during the entire winding operation, including 65 the intermediate positions of the rolls 20 and 22 and I have found that in a machine constructed on that principle, the axis of the spool 12 may move away from the stationary spool 21 during 70 the winding operation in a path which describes an arc, as indicated at 32.

To provide access to the spool 12 for its removal at the completion of the winding operation and for insertion of a new spool, the upper roll 22 is adapted to be swung further about the pivot 22' to the position indicated diagrammatically at 75 22C.

As stated above, I have found that the proper 80 tension of the yarn directly at the periphery of

the spool 12 on which it is being wound may be effected by a differential of speeds between the three equally spaced winding rolls in engagement with the yarn, whereby to exert a drag on the yarn at the points of contact of the winding rolls. 85 As indicated diagrammatically in Fig. 5, wherein I have shown, by arrows, the direction of rotation of the rolls 20, 21 and 22 for the overwinding operation, I provide this differential of speed and resultant frictional drag on the yarn by making 90 the roll 22, which is the initial roll with which the yarn comes in contact as it enters the spool, an idle roll, and by making the rolls 20 and 21 driven rolls with the roll 21 rotated at slightly greater peripheral speed than that of the roll 20. 95 To insure equality in the amount of yarn wound in the underwound and overwound directions of rotation, I preserve this same relationship for the underwinding, whereby, when the direction of rotation of the rolls is reversed, as indicated 100 by arrows in Fig. 6, the roll 21 with which the yarn initially comes into engagement is an idle roll and the rolls 20 and 22 are driven rolls with the roll 22 rotating at a speed which is slightly greater than that of the roll 20. 105

110 Referring now to Figs. 7 and 8 I will describe first the general assembly of my novel setting frame. As there indicated, the creel 3 is supported at the proper elevation at what I shall designate as the rear of the setting frame. The 115 frame of the setting frame has the two vertically extending side members 50 and 51 in which are mounted the winding rolls 20, 21 and 22 in a manner to be described more in detail hereafter. An electric motor 52 or other suitable power source 120 is provided for driving the winding rolls in either their overwinding or underwinding directions of rotation—the motor 52 being connected to the winding rolls by suitable gearing and clutches hereinafter to be described in detail.

125 For the purpose of permitting the above described divergence of the rolls as the spool fills, the rolls 20 and 22 are mounted in movable bearings and are yieldingly urged toward the stationary roll 21 by pneumatic means which includes the cylinder 113. As will appear, the mechanism connecting the cylinder 113 and the winding rolls is also adapted to move the winding rolls 22 from its winding position to its open position indicated at 22C to provide access for removal of the spool 12 which has been wound and 130 insertion of a new spool in winding position.

The side frame members 50 and 51 also rotatably support the measuring rolls 5 and 6, the bottom roll 6 being fixed in position and the top roll 5 being mounted in movable bearings 600 135 which may be elevated or lowered in the side slots 55 in the frame members 50 and 51.

To describe first the mountings of the rolls 20 and 22 whereby they may be moved toward and away from the spool 12—the winding roll 22 (Figs. 9 and 11) is carried on the shaft 80 which is mounted at both ends in bearings carried by pivoted housings 81 and 82 rotatably mounted in the side frame members 50 and 51. The details 140 of these mounting elements are illustrated in Fig. 12 in which are shown the bearings 83 and 84 carrying the ends of shaft 80 and in turn carried by the pivoted housings 81 and 82 respectively. Both housings are constructed in the general 145 form of a crank, the housing 81 having a vertically rising crank arm portion 90 integral with and extending from a hub 92 journalled in the frame 50 of the machine. The hub 92 is reduced in cross-section at 93 to receive a gear 94 fixed to 150

the hub 92 by means of the dowel 95 and screw 96 passing through aligned holes in the gear 94 and hub 92. A similar crank housing to be described, is provided for the bearing 84 on the opposite end of shaft 80 and it is apparent that as a result of this construction, rotation of the gear 94 rotates the hub 92, thereby rotating the crank arm 90 of the housing 81 and swinging the roll 22 about the axis of hub 92.

0 The gear 94 is one element in a train of gears which I shall refer to as the pressure gears, rotated pneumatically by a piston in cylinder 113 (Fig. 8) whereby a yielding pressure of the driving roll 22 (and, as will appear, also the driving 5 roll 20 against the spool) is effected.

Referring now to Figs. 9 and 12, the aforesaid pressure gear 94 meshes with idler gear 105, rotatably mounted on the stud shaft 106 fixed in the frame member 50. The gear 105 meshes with 0 the gear 98 which is rotatably mounted on the shaft 69 (Fig. 13) and in turn meshes with the gear segment 99 keyed to the shaft 101.

The shaft 101, as indicated in Figs. 8 and 11, extends across the machine and has bearings in side frames 50 and 51. Intermediate its length the shaft 101 carries rigidly fixed to it the pinion 110 which meshes with the rack 111 carried by the plunger 112 which is pneumatically elevated and depressed in the cylinder 113 in a manner to 5 be described more in detail hereinafter.

The shaft 101 carries rigidly secured to its extremity opposite to that carrying the gear segment 99 and adjacent the frame 51 of the machine, (Fig. 11) a second segment 120 identical 15 with the segment 99. The segment 120 is connected, through a second set of pressure gears mounted adjacent the frame 51 of the machine, to crank housings carrying the opposite ends of the rolls 20 and 22 from those carried by crank 10 housings rotated by the gears leading from the segment 99, whereby pressure is applied to the movable rolls 20 and 22 from both ends thereof.

The pressure gears leading from the gear segment 120 are illustrated in Fig. 10 of the drawings and as there shown, the segment 120 fixed to shaft 101 meshes with the gear 121 secured to a hub 122 of a crank housing carrying the shaft of the roll 20 in a manner to be described herein-after. The gear 121 meshes with an idler 123 50 rotatably mounted on the stud shaft 124 projecting from the frame 51 of the machine (see also Fig. 12). The idler 123 meshes in turn with the gear 125 which, as indicated in Fig. 12, is fixed, by means of the dowel and screw 127 and 128, on the hub 133 suitably journaled in the frame 51 and integral with the crank housing 82 carrying the bearing 84 for the right hand end of the shaft 80.

The trains of pressure gears on both sides of the machine have corresponding gears of equal pitch diameters and number of teeth and it will be apparent from the above description that elevation and depression of the plunger 112 in the cylinder 113 will move the roll 22 in either a clockwise or counter-clockwise direction, as viewed from either side, depending upon whether the plunger 112 is elevated or depressed and will apply an equal amount of pressure from both ends of the roll, pressing it yieldingly against the 70 spool 12.

To describe now the pressure gears which swing the bearings of the roll 20, that roll is carried by a shaft 140 (Fig. 13) which has the bearing 141 in the arm 142 of a crank housing, the hub 143 75 of which is journaled in the frame member 50 of

the machine, and carries the aforesaid pressure gear 98. The pressure gear 98 is not fixed to the hub 143 as was the corresponding gear 94 associated with the roll 22, but carries a pin 151, the enlarged end 152 of which has a sliding fit in the slot 153 of the hub 143, which slot, as indicated in Fig. 16, is arcuate in shape. At certain times, and in a manner hereinafter to be described, rotation of gear 98 in a counter-clockwise direction moves the end 152 of the pin 151 into abutment with 10 the end 154 of the slot 153 to move the hub 143 and housing 142 to swing roll 20 in the same direction and it is apparent that approximately one-half rotation of the gear 98 in a clockwise direction is permitted without swinging roll 20. 15 The gear 98 is connected, as described above, with the gear segment 99 (Fig. 9) fixed on the pneumatically rotated shaft 101.

On the opposite side of the roll 20, from that just described, the shaft 140 has a bearing 160 20 in the crank housing 161 which has a hub 122 journaled in the frame 51 of the machine, which hub carries the gear 121. The gear 121 is connected to the hub 122 by a pin 163 having a head 164 working in an arcuate slot 165 identical in construction and function with the arcuate slot 153 in the hub 143 on the opposite side of the machine. The gear 121, as stated above, meshes with the segment 120 (Fig. 10) which is fixed to the end of pneumatically rotated shaft 101. 30

Referring now to Fig. 11, rotation of shaft 101 is effected by means of pinion 110 fixed to shaft 101 and meshing with rack 111 carried by piston rod 112 elevated and depressed by a double acting piston 200 sliding in the cylinder 113. 201 indicates a three-way valve adapted selectively to elevate or depress the piston 200 pneumatically or to assume a release position in which the piston 200 can be elevated or depressed at will whereby the rolls 20 and 22 can be manually swung about their pivots.

The valve 201 communicates at 202 with a supply of compressed air and exhausts through a port 203 disposed diametrically opposite the supply port 202. The pipe 204 communicating with the port 205 connects the valve to the upper end of the cylinder 113, above the piston 200, and the pipe 206 leading to the port 207 brings the valve into communication with the lower part of the cylinder 113 below the piston 200. It will be noted that the ports 205 and 207 are diametrically opposite each other on a diameter which is perpendicular to the diameter along which the ports 202 and 203 are in alignment. The valve 201 is fitted with a suitable hand lever, not shown, whereby it may assume the three positions indicated in Figs. 11, 17 and 18.

The valve 201 is drilled to provide a conduit 210 extending diametrically across the valve 201, which conduit, when disposed in the position indicated in Fig. 11, brings the upper and lower ends of the cylinder 113 into communication with each other whereby the piston 200 may be elevated or depressed at will and the rolls 20 and 22 may be manually swung about their pivots.

The valve 201 is also drilled to provide two conduits 211 and 212 which are perpendicular to each other, each of which is disposed at an angle of 45° to the diametrical conduit 210. On the opposite side of the conduit 210 from the conduits 211 and 212, the valve 201 is drilled to provide an angular conduit 213, each end of which is disposed at a distance of 45° around the circumference of the valve 201 from the nearest end of conduit 210.

The valve which is constructed as above described, if rotated to the position indicated in Fig. 17, disposes the connecting conduits 211 and 212 in position to bring the port 202 into communication with the port 207 whereby compressed air entering the port 202 will be conducted through the pipe 206 to the lower end of the cylinder 113, thereby elevating the piston 200. At the same time the upper end of the cylinder 113, above the piston 200, is in communication with the exhaust pipe 203 as a result of the position assumed by the conduit 213 which brings the port 205 into communication with the exhaust port 203. This elevation of the piston 112 will cause clockwise rotation of the segment 99, as indicated by the arrow in Fig. 9, which will cause counter-clockwise rotation of the gear 98 which meshes with the segment 99. This counter-clockwise rotation of the gear 98 will cause the end 152 of pin 151 carried by the gear 98 (Fig. 16) to abut the end 154 of the slot 153 in the hub 143 to swing roll 20 to its position indicated in Fig. 16. The roll 22 (Fig. 9) will also swing in a counter-clockwise direction about the axis of the shaft 100 as a result of gear train 98, 105 and 94. It will be observed that this direction of swing of the rolls 20 and 22 urges those rolls into engagement with the spool 12. This is the running position of the rolls 20 and 22 for winding yarn on spool 12 and it will be noted that as the spool 12 fills with yarn the rolls 20 and 22, which yieldingly press against the spool, are swung away from each other while maintaining their equidistant spacing about the periphery of the spool (Fig. 4). This swinging movement causes a gradual lowering of piston 200 against the pressure in cylinder 113.

After the spool 12 has been wound, it is desirable, as stated above, to swing the top roll 22 away from the spool 12 and to the position indicated at 22C in Figs. 4 and 9, whereby to permit removal of the wound spool and insertion of an empty spool.

To effect this movement the valve 201 is now shifted to the position illustrated in Fig. 18 and in that position the port 202 communicating with the compressed air supply is brought into communication with the port 205 and thence to the upper end of the cylinder 113 at the same time that the lower end of the cylinder is exhausted through the port 207 now in communication with the port 203 through the valve conduit 213. The resultant depression of the piston 200 causes a counter-clockwise rotation of the gear segment 99 in the direction opposite to that indicated by the arrow in Fig. 9 which causes a clockwise rotation of the gear 98.

This rotation of the gear 98 (Fig. 16) moves the pin end 152 in a clockwise direction and as a result of the weight of roll 20, the end 154 of the slot follows the pin end 152 until the roll 20 comes to rest against a convenient stop 106, after which swinging of roll 20 stops, while permitting the gear 98 to rotate approximately one-quarter revolution in a clockwise direction. This amount of rotation of the gear 98 is sufficient, however, to rotate gear 94 in a clockwise direction in an amount sufficient to retract roll 22 to its 22C position, thereby providing the desired access to the spool 12.

The rolls 20, 21 and 22 are each power-driven by certain mechanism now to be described. It will be recalled that the rolls are to be rotated in one direction for overwinding spools and in the opposite direction for underwinding spools and that in the overwound direction (Fig. 5) the roll

22 is, in my preferred embodiment, an idler roll and the rolls 20 and 21 are driven at different relative speeds, whereas in the underwound direction (Fig. 6) the roll 21 is an idler and the rolls 20 and 22 are driven in a direction opposite to that for the overwinding and at the same speeds as the rolls 20 and 21 respectively were driven in the overwinding direction. These rolls are driven from a motor 52 (Fig. 7) which has reversible connections later to be described.

As indicated in Fig. 11, the motor 52 has an elongated shaft 63 which includes clutch 64, on the end of which shaft the pinion 70 is rigidly mounted. The pinion 70, which is the initial gear in a train of gears which I shall refer to as 15 the power gears, meshes with an idler 65 (see also Fig. 9) fixed to the stud shaft 66 rotatably mounted in a suitable bearing in the frame member 50. Stud shaft 66 also carries rigidly fixed to it pinion 67 which meshes with a gear 68 fixed 20 on the aforesaid shaft 69 in front of the gear 98 (see also Fig. 13). The gear 68 meshes with the gear 72 which is connected to the shaft 60 with which the roll 21 is integral, by means of a one-way clutch illustrated in Figs. 14 and 15. 25

The shaft 60 carries fixed to it at the end seen in Figs. 9 and 14, an annular cap member 30 which has a hub 31 keyed at 32 to the shaft 60. The hub 31 carries loosely mounted thereon the aforesaid gear 72, which has a hub 72A loosely 30 mounted on hub 31, which gear carries fixed to it, by means of suitable dowels or bolts 38, the slotted disc 33, which, upon rotation of the gear 72, may rotate freely within the annular member 30. The disc 33 is one of two elements of a 35 one-way clutch of usual construction and has the tapered slots 34 (Fig. 14) which receive cylindrical rollers 35 whereby rotation of the gear 72 and disc 33 in a counter-clockwise direction, as viewed in Fig. 14, imparts counter-clockwise 40 rotation to the annular member 30 and shaft 60 to which it is fixed, thereby rotating roll 21. When the motor is reversed to rotate gear 72 in the opposite direction, that is clockwise as viewed in Fig. 14, the rollers 35 will be driven to the 45 enlarged ends of their slots and roll 21 may then rotate as an idler in the same direction as the gear 72 is then being driven and at any speed which does not exceed the rotational speed of gear 72. 50

The gear 68 which drives gear 72, is fixed to the shaft 69 as indicated by the spline 40 in Fig. 13. The shaft 69 has also fixed to it the gear 41 meshing with the gear 42 enclosed in the swinging arm 142 of the housing carrying the bearing 141, which gear 42 is fixed to the end of the shaft 140 with which the roll 20 is integral. Thus rotation of the gear 68 imparts rotation to the shaft 69 and gear 41 which rotates the gear 42 and drives the roll 20. The roll 20 is adapted, as above described, to be swung gradually away from the axis of spool 12 during the winding, but as this swinging movement is about the axis of the shaft 69 on which drive gear 41 is mounted, the gears 41 and 42 will always remain in mesh 65 at any position of the roll 20 about the axis of the shaft 69. It will be noted that no clutch mechanism is included in the drive for roll 20. This roll is accordingly power-driven at the same rate of speed but in opposite directions for overwind and underwind. 70

The roll 22 is power-driven from the gear 68 (Fig. 14) through the idler gear 43 rotatably mounted on the shaft 106 in front of the aforesaid pressure gear 105 (see also Figs. 9 and 12). 75

The gear 43 meshes with the gear 44 which is 5 rotatably mounted on shaft 100 in front of the pressure gear 94 and is adapted to rotate the shaft 100 by a one-way clutch mechanism. The gear 44 is connected by means of the dowel 45 and screw 46 to a slotted disc 47 which, as indicated in Fig. 14, has four tapered slots 48 each receiving a roller bearing 49. Surrounding the slotted disc 47 is the annular cap member 225 10 which has a hub 226 splined at 227 to the shaft 100, on which hub 226 the aforesaid gear 44 is rotatably mounted. The opposite end of the shaft 100 carries fixed to it the gear 228 which meshes with the gear 229 secured to the end of the shaft 15 22 carrying the roll 22.

By this mechanism rotation of the gear 44 and disc 47 in a counter-clockwise direction, as viewed in Fig. 14, imparts rotation to the shaft 100 and, through the gears 228 and 229, to the roll 22 in 20 a clockwise direction. Idle rotation of the roll 22 in a counter-clockwise direction is permitted by its one-way clutch mechanism when the motor is reversed and gear 44 is driven clockwise.

As stated above, my setting frame includes 25 measuring apparatus which has associated with it means for providing a predetermined limited amount of "take-off" which is available to the operative for the purpose of clamping up the spool after it has been wound and for giving the initial wrap for the next succeeding empty spool.

Referring now to Figs. 7 and 10, the measuring rolls 5 and 6, through which the yarn passes from the creel 3 to the spool 12, are yieldingly pressed toward each other and are rotated by the 30 passage of yarn between the bite of the rolls. Either or both of these rolls may be provided with suitable friction elements of the type commonly provided on such rolls for producing a drag on the yarn and thereby tensioning the same 35 during the winding. The axis of the lower roll 6 is fixed in position and the upper roll 5 is movable toward and away from the roll 6 and is spring-pressed in yielding engagement therewith during the winding operation. The upper roll 5 is carried by bearings 600 which are slidably 40 mounted in the parallel slots 55 provided in the frame members 50 and 51 on each side of the machine (see Figs. 9 and 10). The bearings are spring-pressed in a downward direction by means 45 of a spring 601 disposed between a member 600a fixed to each bearing 600 and the lower extremity 602 of an arm 605, which extremity is apertured to receive freely a pin 603 extending from each member 600a, around which pin the spring 601 is disposed. The pin 603 has an enlarged head 612 against which the extremity 602 of the arm 605 abuts at times to elevate the bearing 600. The arm 605 forms one member of a toggle, the other arm 607 of which is pivoted at 613 to the arm 605 and is secured to a shaft 608 which extends across the machine and which, as indicated in Fig. 8, has bearings in both side frame members 50 and 51. The same toggle construction is provided at the other end of roll 5 and the extremities of shaft 608 have secured to them the hand levers 609. If desired the shaft 608 may be counterweighted as indicated at 610.

Both of the toggle joints 613 have the usual stops against which the joints abut when the 50 toggle elements are straightened past alignment with each other and in my preferred embodiment the stop against which one of the toggle joints 613 abuts, comprises a spring-pressed button 615 which actuates a contact of an electric stop switch 616.

It is apparent that rotation of the hand lever 609 in a counter-clockwise direction, as viewed in Fig. 7, breaks the toggle joint 613 and raises the extremity 602 of the arm 605 against the enlarged head 612 of the pin 603 connected to the member 600a, thereby raising the same and elevating the measuring roll 5. When the parts are returned to the position indicated, by straightening the toggle joint, the spring-pressed button 615 is held inwardly to close the contact in the 10 switch 616 and in this position it will be noted that the measuring roll 5 is yieldingly urged in peripheral engagement with the fixed measuring roll 6.

As indicated in Fig. 10, the roll 6 carries fixed 15 to its shaft a pinion 225 meshing with an idler gear 226 which in turn meshes with a gear 227 fixed to the shaft 228. The gear 227 meshes with a so-called measuring gear 229 fixed to the rotatable shaft 230 to which shaft is also rigidly 20 secured the gear 231. The gear 231 meshes with the gear 232 which in turn meshes with the gear 233. By this train of gears, feeding of the yarn through the measuring rolls 5 and 6 by means of the winding rolls 20, 21 and 22 causes rotation 25 of the gears 232 and 233 in the direction indicated by arrows and these gears form two of the elements of a so-called hunting tooth mechanism which I employ to trip a limit switch after a predetermined amount of yarn has been wound. 30

The hunting tooth apparatus is constructed as follows: The face of gear 232 carries fixed to it the cam 235, (Fig. 20) having a flat cam portion 240, on which cam the lever 241, pivoted at 242 is adapted to ride. The lever 241 has a reduced 35 flange portion 236 forming a squared shoulder 237 adjacent which is pivoted the extension 250 by a pivot 251 passing through the flange 236. The extension 250 has a similar squared shoulder 238 which is bevelled at 239 and by this construction the extension 250 of the lever may be 40 swung in a counter-clockwise direction about the pivot 251 but cannot move in a clockwise direction beyond a position in alignment with the lever 241. 45

Extending downwardly from the extension 250 adjacent the pivot 251 is a tooth 247 adapted at times to be received by the notch 246 on a disc 245, suitably secured to the face of the gear 233 and adapted to rotate therewith. The other 50 extremity of the extension 250 has depending from it a chain 252 connected to a limit switch 253, to be described more in detail hereinafter, which is adapted to be operated to break circuit to the motor 52 upon elevation of the chain 252. 55

From the above description it is apparent that when the gears 232 and 233 assume the positions indicated in Fig. 20, wherein the flat portion 240 on the cam 235 is uppermost, the lever 241 will be disposed in a substantially horizontal position, thereby permitting the tooth 247 to drop into the notch 246 when the notch arrives at the position of Fig. 20. The momentum of the notched disc 245, travelling in the clockwise direction indicated by the arrow, will force the side walls of the notch 246 against the tooth 247 to rotate the extension 250 slightly about its pivot 251 to lift the chain 252 and actuate the limit switch 253. This operation will occur only when the rotation 65 of gears 232 and 233 brings the flat portion 240 of cam 235 and the notch of disc 245 uppermost at the same time and the gears 232 and 233 each have a different but predetermined odd number of teeth so that this position of the cam and notched disc will be assumed only once during 70 75

a predetermined multiple of rotations of the gears 232 and 233.

The ratio of the teeth in the gears 232 and 233 are correlated with the gear ratios in the gear train leading from the gears 232 and 233 to the measuring rolls 5 and 6 to trip the limit switch 253 upon the passage of a predetermined yardage of yarn through the measuring rolls 5 and 6.

For the purpose of making the length of yarn measured by the hunting tooth apparatus, adjustable by lengths of one foot, I make the measuring roll 6 precisely one foot in circumference and I so design the gear ratios that a change of one tooth in one of the gears corresponds to a change of one revolution of the measuring roll 6, that is, a change in one foot of yarn measured. To that end the ratios of gears 225 and 227 is made one to three and the ratios of gears 229, 231, 232 and 233 is such that the number of teeth in the measuring gear 229 determines the yardage of yarn measured, each tooth representing one foot of yarn, so that by replacing the gear 229 with one having, for example, one more tooth than the gear 229 shown in the drawings, the yarn measured will be increased by one foot.

For the purpose of permitting the draw-off of only a predetermined amount of yarn, the hand lever 260 is provided. This lever is freely pivoted on the shaft 228 and carries with it a disc 261 having a cam roller 262 (see also Fig. 20) adapted to abut against and raise the roller 263 surrounding the pivot 251 joining the levers 241 and 250 upon counter-clockwise rotation of the disc 261.

Between the disc 261 and the gear 227, both mounted on the shaft 228, are two ratchets (see Fig. 19), indicated at 265 and 266, secured to shaft 228. Engaging the ratchets 265 and 266 is the double ended pawl 270, the end 270A of which lies in the plane of the ratchet 266 (see also Fig. 10a) and is adapted to engage therewith and the end 270B of which lies in the plane of, and is adapted to engage, the other ratchet 265. The pawl 270 is fixed to a pivot 271 extending from disc 261 to which pivot is also fixed an arm 272 connected by the link 273 to the hand lever 274 pivotally mounted on the upper end of the lever 260. The link 273 is spring-pressed downwardly as by the spring indicated at 275 so that the normal position of the pawl 270 is such that the end 270A engages the teeth of the ratchet 266 and it is apparent that with the pawl 270 in that position, counter-clockwise rotation of the hand lever 260 will rotate the shaft 228 and gear 227 which is fixed to it, thereby rotating gear 226 and the measuring rolls 5 and 6 in a direction to feed yarn from the creel toward the spool. Such rotation is permitted as a result of the engagement of the roller 262, carried by the disc 261 (see also Fig. 20), with the roller 263 surrounding pivot 251 joining the levers 241 and 250, thereby elevating the pivot 251 and lifting the tooth 247 out of the notch 246 to free the gear 233 for the necessary clockwise rotation. A stop 275 fixed to the frame member 51 is disposed in the path of travel of the lever 260 to limit the counter-clockwise throw thereof. A similar stop 276 determines the limit of clockwise rotation of the lever 260.

For the purpose of requiring only a short throw of the lever 260, as determined by stops 275 and 276, I have found it desirable to provide for two throws of lever 260 to unwind the total predetermined amount of yarn desired for clamping up

the wound spool and providing the overlap to commence the winding of the next succeeding spool. Upon retraction of the lever 260 against its stop 276 a second tooth of the ratchet 266 will be in position to be engaged by the end 270A of the pawl and upon a second counter-clockwise rotation of the lever 260 the second half of the desired amount of yarn will be unwound. The lever 260 is then returned against the stop 276 but as I wish to provide that only a predetermined amount of yarn, measured by two throws of the lever 260 can be unwound by the operative, I provide that a third throw of the lever 260 will be ineffectual to unwind more yarn by providing that at the beginning of this throw there will be no tooth in the ratchet 266 in position to be engaged by the end 270A of the pawl 270. Thus it is apparent that a pair of teeth only are positioned to be engaged by the pawl 270 during any given unwinding operation.

As stated above, the gear train leading from the measuring rolls 5 and 6 to the hunting tooth apparatus mounted on the gears 232 and 233 by which the machine is automatically stopped, is adapted to be changed by replacement of the measuring gear 229 to vary, in foot lengths, the amount of yarn measured by the rolls 5 and 6. It is apparent that if the measuring gear 229 is so changed by the substitution of a gear of, say, one tooth more, the gear 227 carrying the ratchet 266, upon being stopped automatically, will come to rest in a position different from that illustrated and one in which the pair of teeth which would have been engaged by the end 270A of the pawl 270 prior to the change would no longer be in the proper position for the manual unwinding.

As stated above, I provide that the ratio between the number of teeth of the gears 225 and 227 is in the proportion of one to three and a change of one tooth in the measuring gear 231 corresponds to a change of one revolution of gear 225 or one-third of a revolution of the gear 227. Accordingly, I provide the ratchet 266 with three pairs of teeth (see Fig. 10b) each pair spaced equidistantly from each other around the ratchet 266, and it is apparent that one of these pairs of teeth will be in position for engagement by the end 270A of the pawl 270, regardless of the change in teeth in the measuring gear 229.

It is sometimes desirable to be able to rotate the measuring rolls 5 and 6 in a direction to unwind the yarn from the spool and in the direction of the creel, such as when the yarn has become tangled about the spool. For that purpose the second ratchet 265 is provided with evenly spaced teeth designed to be engaged by the end 270B of the pawl 270 when that end of the pawl is depressed into engagement with the teeth of ratchet 265 through the elevation of the rod 273 by actuation of the hand lever 274 carried by the lever 260.

Referring now to Fig. 21, I will describe the electric circuits connecting the driving motor 52 with the limit switch 253 and with other switches used to start and stop the motor 52 manually and automatically.

The numerals 401, 402 and 403 indicate power mains leading from a suitable source of three phase sixty cycle current at 550 volts. These three phase leads are connected to a self-main-taining magnetic switch 400 and thence to a reversing switch 404 from which the leads pass to the motor 52. 410 indicates diagrammatically a brake adapted to stop the rotation of the shaft of the motor 52, which brake is normally main-

tained in applied position but is moved to released position by the solenoid 412 connected by leads 413 and 414 to power mains 492 and 401 respectively. Obviously the brake will be released and held in released position when the power is introduced to the motor 52, but will be applied upon interruption of the circuit to the motor.

For the purpose of closing, and maintaining in closed position, the magnetic switch 400, I provide a holding coil 415, which, upon being energized, attracts the switch rod 416 to close the switch 400 across the three phase leads. The holding coil 415 is in circuit with the three phase lead 492 through the lead 417 and is connected by the lead 418, through closed switch 616, to the terminal 420 engaged by the armature 421 of relay 422 which is normally maintained in closed position across terminals 421 and 423 to complete the circuit from the lead 418 through to the lead 424 connected to one pole of the aforesaid limit switch 253. The limit switch is in series with momentary contact switch 430 by means of lead 431 connecting the limit switch to a terminal 432 of the switch. The pivoted switch arm 434 is normally spring-pressed to closed position against the contact 432 and the switch arm 434 is connected by the lead 436 to the terminal 437 disposed adjacent a switch bar 433 mounted on bar 416, which closes circuit between the terminal 437 and a terminal 439 connected by wire 440 to lead 403.

The aforesaid lead 436 is also connected to a switch arm 442 normally spring-pressed to open position, as indicated, but adapted to be closed across the terminal 443 which, by the lead 444 is connected in circuit with the power main 403.

With the device wired as above described, a momentary closing of the starting lever 442 closes the circuit from the wire 444 which, as above indicated, is connected to the power main 403, through the starting switch lever 442 to the normally closed switch 434 through the limit switch 253, through the normally closed armature 421 of relay 422, thence through the holding coil 415 and, by means of the wire 417, back to the power main 492, thereby completing the circuit through the coil 415, which, upon being energized, attracts switch rod 416 to close the magnetic switch whereby to release the brake 410 and start the motor 52.

The starting switch 442 may be instantly released because a holding circuit through the coil 415 has now been established. This circuit commences at lead 402 of the three phase source through the holding coil 415, closed armature 421 of relay 422 through closed limit switch 253, closed switch lever 434, through lead 436, and switch bar 433 which is now closed across terminals 437 and 439 and thence by lead 440 back to power lead 403.

The motor 52 continues to run until manual opening of switch lever 434 of the switch 430, or until opening of the limit switch 253 or until opening of switch 616, which, as above described, is adjacent the joint of the toggle which is opened upon elevation of the measuring roll 5 (see Fig. 7). These three switches are all in series in the above described circuit and when any one of them is opened, it interrupts the circuit to the holding coil 415, thereby permitting the bar 416 to move to the left, as indicated in the diagram, whereby to open the three phase switch.

The wiring circuit to my motor includes also an automatic stop mechanism which functions to stop the machine, in a manner now to be de-

scribed, upon the breaking of any of the yarns leading from the creel to the setting frame.

As indicated in Fig. 21, I may provide, adjacent the reed 4 and between it and the measuring rolls 5 and 6, a second reed 467 having a rod 468 extending across the machine beneath the yarn 1 and in proximity thereto. To this rod 468 is pivoted a large number of switch fingers 461, and I preferably provide as many fingers 461 as there are strands of yarn 1 entering from the creel to the setting frame. The end 462 of each switch finger 461 extends between a pair of adjacent teeth on the reed 467 near the base of the teeth. The other end 463 of the switch finger, which is the heavier end and which therefore tends to rotate the finger in a clockwise direction about the pivot 468, engages a bar 464 made of electrically conducting material. The bar 464 extends crosswise of the machine for the full length of the reed 467 and is insulated from the machine by a suitable insulation mounting 465. A wire 470 connects the bar 464 in a circuit hereinafter to be described.

The switch fingers 461 are each made of electrically conducting material, as is the pivot rod 468 on which they are pivotally mounted and to which they are thereby electrically connected. The pivot rod 468 is carried by brackets 471 and is connected at terminal 472 to lead 475.

From the above description it is apparent that if leads 470 and 475 are connected in an electric circuit, this circuit will be open so long as all of the fingers 461 are maintained in their elevated positions shown in Fig. 21, out of contact with bar 464. The tension in the yarn as it is fed through the reed 467 causes depression of the ends 462 of all the fingers 461, thereby maintaining their ends 463 out of contact with the bar 464 and keeping the circuit open. However, if any one of the strands of the yarn 1 should break, during the winding, the tension on that strand will be released, as indicated in Fig. 22, permitting its corresponding switch finger 461 to drop and close contact with the bar 464 thereby closing the circuit from lead 470 to lead 475. The lead 475 is connected to the secondary 480 of a step-down transformer, which in turn is connected, by means of the wire 481, with the solenoid 482 of a relay 483, the armature 484 of which is normally spring-pressed to open position away from the terminals 485 and 486. The circuit through the coil 482 is completed by means of the wire 470 which, as above noted, is electrically connected to the conductor bar 464.

The primary 490 of the transformer is connected by the lead 491 to the three phase power main 492 between the magnetic switch 400 and motor 52. The other terminal of the primary is connected by the lead 493 to the power main 403 of the three phase source and it is thus apparent that when the magnetic switch 400 is closed, an electric circuit is established through the primary 490 of the transformer.

The aforesaid armature 484 of relay 483, upon being elevated, closes circuit across terminals 485 and 486, the latter of which is connected to a power source by means of the wire 495 connected to the wire 491 which, as above noted, leads to power main 402. The other terminal 485 of relay 483 is connected by the wire 496 to the coil 497 of the aforesaid relay 422, the circuit through which is completed by means of the wire 498 which connects to the aforesaid wire 493.

The relays 483 and 422 are both time delayed relays and are each provided for this purpose

with a dashpot of well known construction. Because of dashpot 500, the relay 483, upon being energized, takes a period of two seconds before complete closing of the armature 484 across the terminals 485 and 486. The relay 422, on the contrary, is normally maintained in closed position and when it opens, through energizing of the coil 497, it opens instantly. It is provided, however, with a dashpot 501 whereby when coil 497 is again deenergized the movement of the armature 421 to closed position is delayed and takes a period of ten seconds until electrical contact is made.

With the device electrically connected as above described, when the magnetic switch 400 is closed by a momentary closing of switch arm 442 of momentary contact switch 430 to start motor 52 as above described, the primary 490 of the transformer is energized by the flow of current through the leads 491 and 493. At the instant of starting of rotation of the winding rolls 20, 21 and 22, the strands of yarn may be quite slack which might permit one or more of the fingers 461 to rest in electrical contact with the conductor bar 464 (Fig. 22). Such contact would complete a circuit through the leads 470 and 475 to the coil 482 of relay 483 to energize the same and attract its armature 484. If the relay 483 were adapted to close instantly, the machine would again stop as a result of completion of the circuit through armature 484 of relay 483, from lead 491 through lead 496 to coil 497 of relay 422, thus attracting armature 421 to interrupt the circuit to holding coil 415 of three phase switch 400. To prevent the machine thus stopping immediately as a result of slack in the yarn and to provide a brief time interval during which the yarn may assume its taut position, I provide dashpot 500 on relay 483 to effect a two second delay in closing of armature 484. This interval of two seconds is sufficient to permit the yarn to become taut, thereby retracting the fingers 461 to their elevated positions of Fig. 21, out of contact with bar 464. This retraction of the switch fingers 461 again deenergizes the coil 482 of relay 483 before its armature 484 has had time to complete the circuit, whereupon the armature returns to its fully open position of Fig. 21. The machine continues to run, if not stopped by one of the switches 616, 253 or 434, until one of the strands of yarn breaks, which will again cause energizing of coil 482 of relay 483, and, after a two second interval during which the finger 461 will remain in its contacting position of Fig. 22, coil 497 of relay 422 will be energized, thereby opening switch 480 and stopping the motor. The opening of switch 480 deenergizes the primary 490 of the transformer thereby instantly opening armature 484 of relay 483, and if the armature of relay 422 also immediately returned to its closed position, the operative could then start the machine without mending the broken strand 55 of yarn and the machine would run for two seconds before relay 484 was again opened. If the operative did not wish to take the pains to tie in the broken strand of yarn she could make the machine continue to run by manually holding up the switch finger 461 until the broken end is caught between the rolls 5 and 6 when the tension of the yarn would hold the finger 461 in its elevated position and the machine would continue to run without the broken end 70 having been tied in. To insure against such

inefficient operation and to induce her to tie the broken ends, I provide the dashpot 501 on the relay 422 to delay the closing of its armature 421 to starting position for a period of ten seconds. The operator can easily tie in the yarn within this inactive period and is thereby induced to do so.

While I have specified certain time intervals for the delayed actuation of the relays, obviously different time intervals can be employed if desired by adjustment of the dashpots in the usual manner.

As stated above and as described in connection with diagrammatic Figures 5 and 6 of the drawings, in the preferred embodiment of my invention the initial winding roll with which the yarn comes in contact for either overwinding or underwinding, is an idle roll, the next roll is driven at a predetermined rate of speed and the last roll is driven slightly more rapidly. For some purposes it may be desirable to make the initial roll, in either the overwinding or underwinding direction of rotation, a driven roll and I have provided a modification of my preferred embodiment in which the initial roll is a driven roll, the second roll is driven at a rate of speed slightly greater than that of the initial roll, and the third roll is driven at a rate of rotation slightly greater than that of the second roll in the series. As will appear from a detailed description of my modification, this relationship is preserved for either the overwinding or underwinding directions of rotation.

Fig. 23 of the drawings is a view illustrating such modification and corresponds to Fig. 9 of the drawings of the preferred embodiment of my invention. The pinion 70A corresponds to the pinion 70 of Fig. 9 and is mounted on the drive shaft of a reversible electric motor connected in an electric circuit identical with that described in connection with Figs. 21 and 22. The pinion 70A meshes with a large gear 530 which is fixed on a shaft 531. The shaft 531 carries splined to it the gears 502 and 503, which gears are cast on the same hub, indicated at 584, which hub, with the gears 502 and 503, may be slid longitudinally of the shaft 531 and for that purpose is grooved at 505 to receive trunnions 506 mounted on the ends of a bifurcated member 507 on the end of arm 508 fixed on the end of shaft 509 which is suitably supported adjacent the frame of the machine and provided with a shifting hand lever 510 rigidly secured to the upper end of the rod 509 and adapted to rotate the same. By this mechanism it is apparent that shifting of the hand lever 510 will shift gears 502 and 503 from their positions indicated in Fig. 24 in which the gear 503 is in mesh with a gear 511 and the gear 502 is not in mesh with any gear, to a position wherein the gear 503 is out of mesh and the gear 502 meshes with a gear 512.

The gears 511 and 512 are secured to a shaft 513 to which is secured the roll 21, which roll, as in my preferred embodiment, is mounted in fixed bearings (see Fig. 15).

The aforesaid shaft 531 which is rotated by the gear 530 fixed to it, like the shaft 69 (Fig. 9) of the preferred embodiment of my apparatus, carries fixed to it a gear 41A, corresponding to gear 41 (Fig. 13) of the apparatus of my preferred embodiment, by means of which roll 20 is rotated. This roll, as in my preferred embodiment, is mounted in a movable bearing adapt-

ed, by pressure gears, to swing about the axis of the shaft 531.

The gears 502 and 503 at times mesh respectively with idlers 520 and 521 mounted on suitable stud shafts, which idlers in turn mesh respectively with gears 522 and 523 which, as shown in Fig. 25, are secured to the shaft 524 rotatably mounted in the frame of the machine. The shaft 524 corresponds to the shaft 100 (Fig. 12) of my preferred embodiment and carries the gear 228A, by means of which the winding roll 22 is driven, the said winding roll being mounted, as before, on a shaft which has a bearing adapted to swing about the axis of the shaft 524 toward and away from the spool during the winding operation.

The swinging of the rolls 21 and 22 toward and from the spool being wound, is effected in my modified embodiment in the same manner as in the preferred embodiment, namely, by a set of pressure gears (not shown) leading from a pneumatic source of power.

With the modification constructed as above described, the motor is rotated to drive the pinion 76A in the desired direction, depending upon whether overwinding or underwinding is desired. For overwinding, the rolls are rotated counter-clockwise for which purpose the pinion 76A will be driven in a counter-clockwise direction as viewed in Fig. 23, the gear 530 will rotate clockwise as will the gears 502 and 503 splined to the shaft 531 carrying the gear 530. In this direction of rotation it is desired that the initial roll 22 rotate at a certain predetermined rate of speed, the second roll 20 rotate at a speed slightly greater than that of the roll 22, and the roll 21 be driven at a speed slightly greater than that of the roll 20. For this purpose the gears 502 and 503 are disposed in the position in which they are shown in Fig. 24, by movement of the hand lever 510 if necessary, in which case the gear 503 meshes with the gear 511 and also with idler 521 which, in turn, drives gear 523 which rotates the roll 22. Gear 523 has a greater number of teeth than gear 503, which latter gear in turn has a greater number of teeth than gear 511 which results in a moderate rotation of roll 22, a slightly faster rotation of roll 20 and a still faster rotation of roll 21, as is desired for the overwinding or counter-clockwise direction of rotation of the winding rolls.

In the underwinding direction of rotation the rolls 20, 21 and 22 each rotates clockwise by a reversal of direction of the motor which drives the pinion 76A, which is now also made to rotate clockwise. To produce the desired ratio of speeds, namely, that in which the roll 20 rotates faster than the roll 21 and the roll 22 in turn rotates faster than the roll 20, the hand lever 510 is shifted until the gear 503 comes out of mesh with the gear 511 and idler 521, and the gear 502 meshes with the gear 512 and with idler 520. It will be noted that this shifting of the gears 502 and 503 on shaft 531 does not change the speed of roll 20 which rotates at the same speed both clockwise and counter-clockwise, determined partly by the ratio of pinion 76A and gear 530. The speed of rotation of roll 21 is, however, decreased relative to the speed of roll 20 and the speed of roll 22 increased relative to the speed of rotation of roll 20 by this shifting of the hand lever 510, because gear 512 has a greater number of teeth than gear 502 and the gear 502 in turn has a greater number of teeth than the gear 522, which latter gear, at this time,

is rotated through meshing of the gear 502 with idler 520.

In this manner all of the rolls are made power-driven in both the overwinding and underwinding directions in my modified embodiment and the desired ratio of speeds to produce tensioning of the yarn adjacent the spool is preserved regardless of direction of rotation.

Obviously my preferred embodiment is subject to other modifications within the spirit of my invention which is to be limited only as indicated by the appended claims. Thus, although I have described in both my preferred and modified embodiments, sets of gear trains both for driving the several rolls at their respective predetermined speeds for rotating the receiver and also for swinging the rolls to apply pressure to the receiver or spool being wound, I do not wish to limit myself to such mechanism but can obviously employ other mechanism, such as belt drives to perform either or both of those functions. Nor is the predetermined speed at which each of the power-driven rolls is rotated necessarily a constant speed but may be a variable predetermined speed effecting an increased differential of speed between the winding rolls as the spool fills whereby to increase the tension on the yarn and thereby counteract the increased tendency toward puffiness which may obtain after a considerable amount of yarn has been wound on the spool. Obviously hydraulic, electrical or any means other than the pneumatically operated apparatus described may be employed for exerting the yielding pressure of the swinging winding rolls against the spool and for removing the top roll to replace the wound spool with an empty one, provided the means chosen effects a yielding pressure which may be gradually applied and of any desired amount.

In the diagrammatic views of Figs. 1 to 6 inclusive, I have illustrated the winding rolls as being disposed at substantially equal intervals about the periphery of the spool during the entire winding operation. For an effective winding operation it is not essential that the rolls assume this position at the very beginning of the winding operation because at that time the periphery of the spool with one or two layers of yarn is relatively small and proper tensioning of the yarn does not require equal spacing of the rolls throughout that small distance. As described in detail in my copending application Serial No. 45,839 filed concurrently herewith, I may wish to direct the yarn in a straight line path from the guide roll 11, tangentially of the spool without being deflected by roll 21 during underwinding, or by roll 22 during overwinding, which may be more conveniently accomplished by spacing the rolls 21 and 22 widely apart and not equidistant relative to each other and to roll 20 during the initial winding rotation. In that event, as illustrated in Fig. 7, I so position the pivots of the cranks supporting the rolls 20 and 22 that an equidistant spacing of the three rolls is assumed shortly after the winding commences.

I claim:

1. In a frame for winding yarn on a receiver, the combination of a plurality of winding rolls adapted to be disposed in peripheral engagement with a receiver for winding yarn thereon, mountings for said rolls including crank supports for a plurality of said rolls adapted to position the rolls at substantially equal intervals around the periphery of said receiver, and pivots for said crank supports positioned to maintain a sub-

stantially equidistant spacing of the rolls about the periphery of the receiver during divergence of the rolls as the receiver fills.

2. In a frame for winding yarn on a receiver, 5 the combination of three winding rolls adapted to be disposed in peripheral engagement with a receiver for winding yarn thereon, mountings for said rolls including crank supports for two of said rolls adapted to position the rolls at substantially equal intervals around the periphery of said receiver, fluid pressure means actuating said crank supports for yieldingly urging the rolls supported thereon into peripheral engagement with the receiver and pivots for said crank supports positioned to maintain a substantially equidistant spacing of the rolls about the periphery of the receiver during divergence of the rolls as the receiver fills.

3. In a frame for winding yarn on a receiver 20 selectively in an overwind or underwind direction, the combination of three winding rolls adapted to be disposed in succession around the periphery of a receiver, means driving the intermediate roll at a constant predetermined rate of 25 speed selectively in either the overwind or underwind direction, driving means for another roll adapted selectively to effect idle rotation thereof in the overwind direction and driven rotation in the underwind direction at a predetermined rate of 30 speed greater than that of the intermediate roll, and driving means for the third roll adapted selectively to effect idle rotation thereof in the underwind direction and driven rotation in the overwind direction at a predetermined rate of 35 speed greater than that of the intermediate roll.

4. In a frame for winding yarn on a receiver, 40 the combination of means for rotating a receiver to wind yarn thereon, auxiliary means for feeding yarn independently of the rotation of the receiver, means for actuating said auxiliary feed means whereby to feed the yarn and means associated with said actuating means to limit to predetermined lengths the amount of yarn feedable by 45 said auxiliary means.

45 5. In a frame for winding yarn on a receiver, the combination of means for rotating a receiver to wind yarn thereon, auxiliary means for feeding yarn independently of the rotation of the receiver, means for actuating said auxiliary means whereby to feed the yarn and means rendering inoperative the said actuating means upon the feeding of 50 a predetermined amount of yarn by said auxiliary means.

6. In a frame for winding yarn on a receiver, 55 the combination of means for rotating a receiver to wind yarn thereon, feed rolls engaging the yarn for feeding the same independently of the rotation of the receiver, ratchet means for rotating said feed rolls whereby to feed the yarn, pawl 60 means engaging said ratchet means for rotating the same and means rendering inoperative said pawl means upon the feeding of a predetermined amount of yarn by said feed rolls.

7. In a frame for winding yarn on a receiver, 65 the combination of means for rotating a receiver to wind yarn thereon, auxiliary means for feeding yarn independently of the rotation of the receiver, reversible means for actuating said auxiliary means whereby selectively to feed yarn toward or away from the receiver and means rendering inoperative said actuating means upon the feeding, by the auxiliary means, of a predetermined amount of yarn toward the receiver.

8. In a frame for winding yarn on a receiver, 70 the combination of a plurality of winding rolls

adapted to be disposed in peripheral engagement with a receiver for winding yarn thereon, mountings for said rolls adapted to position the rolls at unequal intervals around the periphery of said receiver at the beginning of the winding operation and means movably supporting a plurality of said mountings positioned to swing the rolls into substantially equidistant relationship about the periphery of the receiver while permitting divergence of the rolls as the receiver fills.

9. In a frame for winding yarn on a receiver, 10 the combination of three winding rolls adapted to be disposed in peripheral engagement with the receiver for winding yarn thereon, mountings for 15 said rolls adapted to position the rolls at substantially equal intervals around the periphery of said receiver, the mounting for one of said rolls being fixed to maintain its roll in fixed axial position, means for movably supporting the other mountings, positioned for directing the movement of 20 said movable mountings to maintain a substantially equi-distant spacing of the rolls about the periphery of the receiver during divergence of the rolls as the receiver fills.

10. In a frame for winding yarn on a receiver, 25 the combination of three winding rolls adapted to be disposed in peripheral engagement with the receiver for winding yarn thereon, mountings for 30 said rolls adapted to position the rolls at substantially equal intervals around the periphery of said receiver, the mounting for one of said rolls being fixed to maintain its roll in fixed axial position, the mountings for the other rolls including cranks for movably supporting said other rolls, pivots for 35 said cranks so positioned relative to the length of said cranks as to maintain a substantially equidistant spacing of the rolls about the periphery of the receiver during divergence of the rolls as the receiver fills, and means for driving at least two 40 of said rolls.

11. In a frame for winding yarn on a receiver, 45 the combination of a plurality of winding rolls adapted to be disposed in peripheral engagement with the receiver for winding yarn thereon, mountings for said rolls adapted to position the 50 rolls at substantially equal intervals around the periphery of said receiver, including a crank support for the uppermost roll, a pivot for said crank support and fluid pressure means for swinging the crank support to move the said uppermost roll 55 from its winding position contiguous to the receiver to a position remote from the receiver for replacement of a filled receiver with an empty one.

12. In a frame for winding yarn on a receiver, 60 the combination of a plurality of winding rolls adapted to be disposed in peripheral engagement with a receiver for winding yarn thereon, mountings for said rolls positioning the rolls at unequal 65 intervals around the periphery of an empty receiver, and means movably supporting a plurality of said mountings positioned to move the rolls into substantially equidistant spacing during divergence of the rolls as the receiver fills.

13. In a frame for winding yarn on a receiver, 70 the combination of a plurality of winding rolls adapted to be disposed in peripheral engagement with a receiver for winding yarn thereon, mountings for said rolls, including crank supports for a 75 plurality of said rolls and pivots for said cranks, the lengths of said crank supports and the positions of said pivots being such as to dispose the said rolls substantially equidistantly around the periphery of the receiver during the winding and

to preserve such equidistance during subsequent divergence of the rolls as the receiver fills.

14. In a frame for winding yarn on a receiver, the combination of means for rotating a receiver to wind yarn thereon, rolls engaging the yarn and adapted to be rotated by the run of the yarn to the receiver, measuring means connected to the rolls for measuring selected predetermined lengths of yarn wound on the receiver and adapted automatically to stop rotation of the receiver and run of the yarn upon the winding of a desired length of yarn, auxiliary means for rotating said rolls independently of the rotation of the receiver to draw off a limited predetermined length of yarn toward the receiver and mechanism co-ordinating said auxiliary means with said measuring means for measuring different selected lengths of yarn while limiting the draw-off to a constant predetermined length.

15. In a frame for winding yarn on a receiver, the combination of three winding rolls adapted to be disposed in succession around the periphery of a receiver for winding yarn thereon, the roll first engaged by the yarn as it passes to the receiver being an idle roll, means for driving the second roll at a predetermined peripheral speed, means for driving the third roll at a predetermined peripheral speed which is greater than that of said second driven roll, and means for varying the rate of speed of the third roll to increase the differential in speed between it and said second roll during winding whereby to increase the tension on the yarn during winding.

16. In a frame for winding yarn on a receiver, the combination of three winding rolls adapted to be disposed in succession around the periphery of a receiver for winding yarn thereon, means for driving at a predetermined peripheral rate of speed the roll first engaged by the yarn as it passes to the receiver, means for driving the second roll at a predetermined peripheral speed which is greater than that of the first roll, means for driving the third roll at a predetermined peripheral speed which is greater than that of said second driven roll, means for varying the rate of speed of said second roll to increase the differential in speed between it and said first roll during winding, and means for varying the rate of speed of the third roll to increase the differential in speed between it and said second roll during winding whereby to increase the tension on the yarn during winding.

17. In a frame for winding yarn on a receiver, the combination of a plurality of winding rolls adapted to be disposed in peripheral engagement with a receiver for winding yarn thereon, a mounting for each of said rolls, means fixedly supporting one of said mountings to maintain the axis of its roll in fixed position during the winding, and means movably supporting the mountings for the remaining rolls adapted to guide the movement of said latter mountings with relation to said fixed mounting to maintain an approximate equidistant spacing of the rolls about the periphery of the receiver during divergence of the rolls as the receiver fills.

18. A frame as defined in claim 17, in which the axis of the receiver is free to move away from said fixed roll to preserve said equidistant spacing as the receiver fills.

19. A frame as defined in claim 17, which includes pressure means yieldingly urging the rolls against the periphery of the receiver during the winding.

20. A frame as defined in claim 17 in which the

means movably supporting the movable rolls positions the rolls at unequal intervals at the beginning of the winding operation and guides them into equidistant spacing during divergence of the rolls as the receiver fills and maintains said equidistant spacing until the winding is completed.

21. In a frame for winding yarn on a receiver, the combination of a plurality of winding rolls adapted to be disposed in peripheral engagement with a receiver for winding yarn thereon, mountings for said rolls including crank supports for a plurality of the rolls and pivots for said crank supports, the lengths of said crank supports and the positions of said pivots being such as to dispose the said rolls at slightly unequal intervals around the periphery of an empty receiver and to direct the rolls into equal spacing as the receiver fills, said equal spacing being thereafter maintained until the winding is completed.

22. In a frame for winding yarn on a receiver, the combination of three winding rolls adapted to be disposed in peripheral engagement with a receiver for winding yarn thereon, one roll having a fixed axis and the other two rolls being mounted on pivoted cranks so that the rolls diverge from each other as the receiver fills, the rolls being so disposed about an empty receiver that the space between two rolls is greater than the spaces between the other rolls for access of yarn to the receiver through greater space without deflection by a roll on either side of it, the lengths and positions of said cranks being such with relation to the axis of the fixed roll that the rolls move into substantially equal spacing after the run has commenced and are preserved equally spaced until the run is completed.

23. In a frame for winding yarn on a receiver selectively in an overwind or underwind direction, the combination of three winding rolls adapted to be disposed in succession around the periphery of the receiver, means driving the intermediate roll at a constant predetermined rate of speed selectively in either the overwind or underwind direction, driving means for another roll adapted selectively to drive the roll in the overwind direction at a rate of speed which is less than that of the intermediate roll and to drive the roll in the underwind direction at a speed which is greater than that of the intermediate roll and driving means for the third roll adapted selectively to drive the roll in the overwind direction at a rate of speed which is greater than that of the intermediate roll and to drive the roll in the underwind direction at a speed which is less than that of the intermediate roll.

24. The frame as defined in claim 13 in which there are three winding rolls successively engaged by the yarn as it is wound around the receiver, the second of which rolls is driven to rotate at a predetermined rate of speed that is greater than the speed of rotation of the first roll and the third of which rolls is driven to rotate at a predetermined rate of speed greater than that of the second roll.

25. The frame as defined in claim 17 in which there are three winding rolls successively engaged by the yarn as it is wound around the receiver, the second of which rolls is driven to rotate at a predetermined rate of speed that is greater than the speed of rotation of the first roll and the third of which rolls is driven to rotate at a predetermined rate of speed greater than that of the second roll.

26. In a frame for winding yarn on a receiver, the combination of three winding rolls adapted to be disposed in peripheral engagement with a

- receiver for winding yarn thereon, a mounting for each of said rolls, one of said mountings being fixed to maintain the axis of its roll in fixed position during the winding, the mountings for the other two rolls including crank supports and pivots for the cranks, the lengths of said crank supports and the positions of said pivots being such as to dispose all said rolls substantially equidistantly around the periphery of the receiver
5. 10. during winding and to preserve such equidistance during subsequent divergence of the rolls as the receiver fills, means for driving the first roll engaged by the yarn as it passes to the receiver at a predetermined rate of speed, means for driving
15. the second roll engaged by the yarn at a predetermined rate of speed that is greater than that of the first roll and means for driving the third roll at a predetermined rate of speed which is greater than that of the second roll.
20. 27. A frame of the character described in claim 26 which is adapted to wind yarn on a receiver selectively in an overwind and an underwind direction and has means for reversing the direction of rotation of the three rolls while preserving the
25. said drive speed relationships.
28. The method of winding yarn tightly on a rotating receiver which consists in engaging the yarn on the receiver at three spaced points around the periphery of the receiver, winding the yarn on the receiver through rotation of the receiver while tensioning the wound yarn between the first and second points and again between the second and third points by frictionally urging advance of the
30. 35. yarn at the third point with respect to the advance of the yarn at the second point and frictionally restraining advance of the yarn at the first point with respect to the advance of the yarn at the second point.

29. The method of winding yarn tightly on a rotating receiver which consists in engaging the yarn on the receiver at three points spaced approximately 120° apart around the periphery of the receiver, winding the yarn on the receiver through rotation of the receiver while tensioning the wound yarn between the first and second points and again between the second and third points by frictionally urging advance of the yarn at the third point with respect to the advance of the yarn at the second point and frictionally restraining advance of the yarn at the first point with respect to the advance of the yarn at the second point and maintaining said approximate 120° spacing between the points during divergence of the points as the receiver fills.

30. The method of winding yarn tightly on a rotating receiver which consists in disposing three contact surfaces contiguous to the yarn at three spaced points about the periphery of the receiver and winding the yarn on the receiver through rotation of the receiver while tensioning the wound yarn between the first and second points and again between the second and third points by advancing the second surface faster than the first surface and the third surface faster than the second surface while pressing all three surfaces into frictional contact with the yarn.

31. The method of winding yarn as defined in claim 30 in which said three contact surfaces are disposed at substantially equal intervals around the periphery of the receiver during the winding of the yarn and said substantially equal intervals are preserved until the winding is completed.

CONRAD C. BLOM.

CERTIFICATE OF CORRECTION.

Patent No. 2,192,889.

March 12, 1940.

CONRAD C. BLOM.

It is hereby certified that error appears in the printed specification of the above numbered patent requiring correction as follows: Page 3, first column, line 15, strike out the parenthesis after "spool" and insert the same after the numeral "20" in same line; and that the said Letters Patent should be read with this correction therein that the same may conform to the record of the case in the Patent Office.

Signed and sealed this 24th day of December, A. D. 1940.

(Seal)

Henry Van Arsdale,
Acting Commissioner of Patents.
